UNITED STATES PATENT OFFICE.

EDGAR DIMOND EASTMAN, OF CONCORD, NEW HAMPSHIRE.

FIFTH-WHEEL.

SPECIFICATION forming part of Letters Patent No. 618,649, dated January 31, 1899.

Application filed September 28, 1898. Serial No. 692,091. (No model.)

To all whom it may concern:

Be it known that I, EDGAR DIMOND EASTMAN, a resident of West Concord, in the county of Merrimac and State of New Hampshire, have invented certain new and useful Improvements in Fifth-Wheels; and I do hereby declare the following to be a full, clear, and exact description of the invention, such as will enable others skilled in the art to 10 which it appertains to make and use the same.

My invention relates to an improvement in fifth-wheels for vehicles, the object of the invention being to provide a fifth-wheel which will permit of the easy turning of a vehicle, one that will be practically noiseless, and so construct same as to exclude dust and dirt therefrom.

A further object is to so construct a fifth-wheel as to effectually guard against the accidental displacement of the parts thereof.

A further object is to provide a fifth-wheel which will be simple in construction, neat in appearance, and strong and durable when in use.

With these objects in view the invention consists in certain novel features of construction and combinations and arrangements of parts, as will be more fully hereinafter described, and pointed out in the claims.

In the accompanying drawings, Figure 1 is a perspective view of my improved device, and Figs. 2 and 3 are views in section of the same.

1 represents the lower plate, which is provided on its lower face with parallel flanges 2 for the reception therebetween of the axle (not shown) of a vehicle. The outer edge 3 of the lower plate 1 is curved in the arc of a circle and the inner end of said lower plate is 35 preferably contracted and extends rearward the desired distance. The upper face of the contracted rear end of the plate 1 is provided with a circular enlargement 4, in which a hole or opening 5 is provided for the passage of the pin 13, whereby to pivotally connect said lower plate with the upper plate or member 6.

The upper face of the plate or member 1 where it comes in contact with the upper plate 6 is preferably flat and smooth, and the 50 lower plate at this point is preferably thicker than the contracted portion thereof to with-

stand the wear incident to its constant contact with the upper plate.

The upper plate 6 is rounded or curved in the arc of a circle at its outer end similar to 55 the curve of the outer edge of the lower plate 1, and said curved or rounded edge of the upper plate or member is provided throughout its entire length with a downwardly and inwardly projecting lip 7, whereby to inclose 60 the edge of the lower plate 1 and exclude dust and dirt from between the plates and avoid any possibility of accidental displacement of said plates or members. The upper plate 6 is provided with rearwardly-extending diverging arms or reach-plates 8, which are flanged on their upper faces at their outer edges, as shown at 9. A web or brace 10 connects the reach-plates 8 and has its ends merged into said reach-plates. The lower 70 face of said web or brace 10 is provided with recessed enlargement 11, which forms a bearing or socket for the reception of the circular enlargement 4 and permits same to be turned therein. A hole or opening 12 is provided in 75 the web or brace 10 in alignment with the hole 5 in the portion 4 of the lower plate for the passage of the pin 13, said pin being provided at one end with a head and at its other end with a nut 14. The lower face of the 80 upper plate 6 where it comes in contact with the lower plate is smooth and is provided in its center with a socket 14' for the reception of an elastic device 15—such, for instance, as rubber block or a spring—and a metal block 85 16 is disposed in said socket and by the elasticity of the rubber block 15 is held against the upper face of the lower plate, and hence prevents any tendency of the device to rattle.

The upper face of the upper plate 6 may 90 be provided with any approved block or support 17, to which any approved vehicle-spring may be secured for supporting the vehicle, the use of the head-block heretofore employed being thus avoided.

Various slight changes might be resorted to in the general form and arrangement of the several parts described without departing from the spirit and scope of my invention, and hence I would have it understood that I 100 do not wish to limit myself to the precise details set forth, but consider myself at liberty

to make such slight changes and alterations as fairly fall within the spirit and scope of my invention.

Having fully described my invention, what I claim as new, and desire to secure by Letters Patent, is—

1. In a fifth-wheel, the combination of a lower plate, an upper plate having a socket in its lower face and means in said socket adapted to bear with yielding pressure against the lower plate and means for pivotally connecting said upper and lower plates.

2. The combination with a lower plate, and an upper plate having a socket therein, of a block disposed in said socket and an elastic material in said socket adapted to force said block in contact with the lower plate.

3. The combination with the two members of a fifth-wheel, having parallel wearing-

faces, one of said members having a socket coincident with the wearing-face, of a block in said socket and an elastic device in said socket behind the block whereby to press the latter against the wearing-face of the other member, substantially as set forth.

4. A fifth-wheel comprising two members having flat coöperating wearing-faces, one member adapted for the reception of an axle and the other member adapted for the direct attachment thereto of a vehicle-spring, substantially as set forth.

In testimony whereof I have signed this specification in the presence of two subscribing witnesses.

EDGAR DIMOND EASTMAN.
